(57) **CLAIM**

An ornamental design for a dome shaped structure for use as a planter, as shown and described.

DESCRIPTION

FIG. 1 is a perspective view illustrating my ornamental design for a dome shaped structure for use as a planter;

FIG. 2 is top view of the dome shaped structure shown in FIG. 1;

FIG. 3 is a bottom view of the dome shaped structure shown in FIG. 1; and,

FIG. 4 is a side view of a representative side of the dome shaped structure shown in FIG. 1.

The broken lines in the drawings represent unclaimed environmental subject matter and form no part of the claim.
